UNITED STATES PATENT OFFICE

100,681

DESIGN FOR A CABINET FOR AUTOMATIC PHONOGRAFPHS

Spencer H. Barclay, North Arlington, N. J.

Application May 28, 1936, Serial No. 62,884

Term of patent 14 years

To all whom it may concern:

Be it known that I, Spencer H. Barclay, a citizen of the United States and a resident of North Arlington, in the county of Bergen and State of New Jersey, have invented a new, original, and ornamental Design for a Cabinet for Automatic Phonographs, of which the following is a specification, reference being had to the accompanying drawing forming part thereof.

I claim:

The ornamental design for a cabinet for automatic phonographs as shown.

SPENCER H. BARCLAY.
